LASTING JACK

Filed March 7, 1929

UNITED STATES PATENT OFFICE

HOWARD G. ELLIS, OF WALTHAM, MASSACHUSETTS, ASSIGNOR, BY MESNE ASSIGNMENTS, TO HOOD RUBBER COMPANY, INC., OF WATERTOWN, MASSACHUSETTS, A CORPORATION OF DELAWARE

LASTING JACK

Application filed March 7, 1929. Serial No. 345,080.

This invention relates to improvements in lasting jacks and has for its object to provide a jack upon which a last can be quickly and firmly secured and which can be easily and quickly manipulated by the operator to occupy the different positions necessary in order that a shoe under construction thereon may be operated upon in a convenient manner and with a minimum amount of effort 10 from the operator.

Another object of the invention is to provide a jack with a locking mechanism for a last that is entirely automatic in its action both in locking the last to the last holder 15 and in finally releasing the last so that the latter may be removed from the holder and replaced by another last.

The invention consists in a lasting jack or holder for a last as set forth in the following 20 specification and particularly as pointed out in the claims.

Referring to the drawings:

Figure 1 is a side elevation of a lasting jack embodying my invention, portions of the 25 jack and last being broken away and illustrated in section and the last holder and last being located in their lowermost positions.

Fig. 2 is a view similar to Fig. 1 but illustrating the last holder and last in their uppermost positions and portions of the last and bracket being broken away to save space in the drawings.

Fig. 3 is an enlarged vertical section 30 through the upper part of the last holder, said section being taken on the line 3—3 of Fig. 2.

Like numerals refer to like parts in the several views of the drawings.

In the drawings, 6 is a bracket having a portion 7 which is adapted to be secured to 40 a suitable support preferably a movable conveyor mechanism. The bracket 6 embodies therein an arm 8, the outer end portion of which is divided to form furcations 9 between which a connecting member 10 is mounted upon a pivotal pin 11 which constitutes a horizontal axis and which is, in turn, mounted in the furcations 9.

The connecting member 10 is slotted at 45 12 to receive a ratchet member 13 provided with 50 a plurality of teeth 14 between which are

V-shaped notches 15. The ratchet member 13 is rigidly secured in any suitable manner to the connecting member 10 and in effect forms a part of said member, it being evident that if it is so desired, the ratchet member 55 may form an integral part of the connecting member 10. The teeth 14 and the notches 15 are positioned concentric to the axis of the pivotal pin 11 and are engaged by a pin 16 which is slidably mounted in a sleeve 17 positioned within an opening 18 provided in the arm 8. The pin 16 is provided with a V-shaped end portion 19 which is held in yielding engagement with the teeth 14 and notches 15 of the ratchet member 13 by a spring 20 which surrounds a shouldered portion 21 of said pin, the tension upon the spring being varied by manipulating a plug 22 which has screw-threaded engagement 60 with the sleeve 17.

When the connecting member 10 is located in any of the positions which permit the spring pin 16 to spring into the notches 15, the V-shaped extremity 19 of the pin will engage the bottom of the V-shaped notches and the connecting member may be locked in any of these positions by means of a locking slide 23 which is slidably mounted upon the under side of the furcations 9 and is adapted to be moved into and out of engagement 70 with the teeth 14.

Rotatably mounted upon the connecting member 10 is a holder 24 for a last 25, the latter embodying therein a base portion 26 having an extension 27 formed integral therewith which projects from said base portion through the connecting member 10 and through a recess 28 provided in said connecting member, and a spring 29 is located within the recess 28 and surrounds the extension 27, being held under compression within said recess by means of nuts 30 which have screw-threaded engagement with the extension 27. A friction washer 31 is interposed between the surfaces of the base portion 26 and connecting member 10 and the ease with which the last holder 24 may be rotated upon the connecting member 10 is increased or diminished by increasing or diminishing the tension upon the spring 29 by manipulating the nuts 30. 80 85 90 95 100

Also formed integral with the base portion 26 of the last holder 24 and oppositely disposed to the extension 27 thereof is a tapered last pin 32 which is adapted to fit a correspondingly tapered hole 33 provided in the last 25 and the axes of both the last pin 32 and the extension 27 are coincidental with the longitudinal median line of the last holder 24.

Extending entirely through the last holder 24 upon the longitudinal median line thereof is a bore 34 in which a bolt 35 is slidably mounted. The bolt 35 embodies therein a portion 36 and a portion 37, the latter having screw-threaded engagement with the portion 36 at 38. A spring 39 surrounds the portion 37 and one end of said spring is seated against a shoulder 40 formed upon the bore 34, while the other end of said spring is seated against a head portion 41 formed at the outer extremity of the portion 37. A slot 42 is formed in the opposite end of the bolt portion 36 from that to which the portion 37 is secured for the reception of a last gripping or engaging member 43 which is pivotally mounted upon a sleeve 44 in turn mounted upon a pin 45 which is located adjacent the outer extremity of the last pin 32.

The gripping member 43 has a cam slot 46 formed therein through which a pin 47 mounted in the portion 36 of the bolt 35 extends. The edge of the slot 46 forms a cam surface and a longitudinal movement of the bolt 35 within the bore 34 will cause the gripping member 43 to be rocked laterally of the last pin 32 within the slot 42 and through a slot 48 provided in the last pin 32 in alignment with the slot 42 of the bolt. The action of the spring 39 is such that the bolt 35 will be moved within the last holder 24 in a manner to rock the gripping member 43 to force an edge portion 49 thereof into engagement with the last 25 as illustrated in Fig. 1, at which time a portion of the gripping member 43 will protrude outwardly beyond the periphery of the last pin 32 in a manner to prevent the last 25 from being removed from said last pin.

A stop screw 50 is mounted in the arm 8 of the bracket 6 and when the last holder is located in its uppermost position, the outer extremity of the head portion 41 of the portion 37 of the bolt 35 will engage the head portion of said screw, causing the bolt to be moved longitudinally within the last holder 24 and moving the last gripping member 43 from the position illustrated in Fig. 1 to the position illustrated in Fig. 2, at which time the last 25 may be removed from the last pin 32.

A spring actuated dowel pin 51 is mounted in the base portion 26 of the last holder 24 and projects therefrom into an opening 52 provided therefor in the last 25, thereby preventing said last from being rotated upon the last pin 32.

The general operation of the device hereinbefore specifically described is as follows:— The last 25 is preferably placed upon the tapered last pin 32 when the connecting member 10 and last holder 24 are located in the position illustrated in Fig. 2. At this time the head portion 41 of the bolt 35 is in contact with the head of the screw 50, the screw 39 is under compression and the bolt 35 has been moved longitudinally within the last holder 24 in a manner to move the last gripping member 43 into a position where it is entirely confined within the periphery of the last pin 32, in which position the last 25 may be inserted upon the last pin or removed therefrom without being obstructed by the last gripping member.

After the last 25 has been mounted upon the last pin 32 all that is necessary to lock said last to said pin is to rock the last holder 24 and connecting member 10 upon the axis 11 of the connecting member, and as soon as the head 41 of the bolt 35 is moved out of engagement with the head of the screw 50, the spring 39 will act to move the bolt 35 in a manner to force the last gripping member 43 from the position illustrated in Fig. 2 to the position illustrated in Fig. 1, at which time the last will be firmly secured upon the last holder.

I claim:

1. A last holder for a jack having, in combination, a last pin upon which a last may be positioned, a last gripping member pivotally attached to said pin, and a bolt operatively connected to said last gripping member and adapted to move the same into and out of engagement with a last mounted upon the last pin.

2. A last holder for a jack having, in combination, a last pin upon which a last may be positioned, a last gripping member pivotally attached to said pin, and a bolt yieldingly mounted on said last pin and operatively connected to said last gripping member and adapted to move the same into and out of engagement with a last mounted upon the last pin.

3. A last holder for a jack having, in combination, a last pin upon which a last may be positioned, a last gripping member pivotally attached to said pin and adapted to be confined within the periphery thereof, and means to move the gripping member from within the last pin into the path of a last mounted upon the pin and thereby prevent the removal of the last therefrom.

4. A last holder for a jack having, in combination, a last pin upon which a last may be positioned, a last gripping member pivotally attached to said pin and adapted to be confined within the periphery thereof, and means to actuate said gripping member to cause the latter to protrude beyond the periphery of the last pin whereby a last mount-

ed upon the pin is prevented from being removed therefrom.

5. A last holder for a jack having, in combination, a last pin upon which a last may be positioned, a last gripping member pivotally attached to said pin and provided with a cam slot therein, a bolt yieldingly mounted in said last pin, and a pin mounted in said bolt and extending through the slot of said gripping member, the latter being moved into and out of interlocking relation with a last mounted upon the last pin by the movement of the bolt within said last pin.

6. A jack for a last having, in combination, 15 a bracket, a connecting member pivotally attached to said bracket, a last holder rotatably mounted upon said connecting member, a last gripping member pivotally mounted upon said last holder and adapted to engage a last 20 positioned upon the holder and lock the last thereto, and a bolt operatively connected to said last gripping member, the latter being actuated to release the last by the contact of said bolt with the bracket when the connecting member is moved to a predetermined position.

7. A jack for a last having, in combination, a bracket, a connecting member pivotally attached to said bracket, a last holder rotatably 30 mounted upon said connecting member and embodying therein a last pin, a last gripping member pivotally attached to said pin and provided with a cam slot therein, said gripping member being adapted to engage a last 35 positioned upon the holder and lock the last thereto, a bolt yieldingly mounted in said last holder, and means projecting from said bolt into said slot and operatively connecting the bolt to the gripping member, the latter being 40 actuated to release the last by the contact of said bolt with the bracket when the connecting member is moved to a predetermined position.

In testimony whereof I have hereunto set 45 my hand.

HOWARD G. ELLIS.
